UNITED STATES PATENT OFFICE.

FRANKLIN R. WHITE, OF WATERBURY, AND LEONARD R. CARLEY, OF WATERTOWN, CONNECTICUT, ASSIGNORS TO THE PATENT BUTTON COMPANY, OF WATERBURY, CONNECTICUT, A CORPORATION OF CONNECTICUT.

FLEXIBLE BUTTON.

Application filed June 20, 1928. Serial No. 286,885.

Our invention relates to new and useful improvements in buttons and more particularly to that kind or type of buttons known and referred to as "flexible" or "swivel" buttons.

The invention in its broadest aspect is similar to the button shown in the patent to Leonard R. Carley, No. 1,191,944, dated July 25, 1916, and the present invention is also a companion application to our application filed of even date herewith and executed May 31, 1928.

In the companion application, the button has provided in its head or shell, an anvil or slug for deflecting the prong of a fastening member as the button is being attached to the cloth; whereas the present invention contemplates a similar button but, the cover for the button head is so arranged that the small metal anvil or slug may be entirely dispensed with. This is made possible by having a certain type cover and having a plunger of the fastening machine extend down within the cover during the attaching of the button head to the cloth, this plunger of the machine deflecting and crimping the prong of the fastening member to the button head, and thus accomplishing the same result as in the companion application without the expense, however, of the small anvil in each button.

Another object of the present invention is to provide a swivel button that comprises simply an eyelet, a shell movably secured with relation to the eyelet, and a cover on the shell so constructed that a plunger from the machine may pass therein and deflect and crimp a fastening member, but later will secure the eyelet to the goods and thus, of course, secure the button.

Still another object of the invention is to provide a button that possesses extreme flexibility, in other words, the head being capable of a shifting movement on its eyelet such as in the companion application, and to further form an opening therein and crimp the fastening member as the button is applied, thus making an extremely simple and efficient form of button and one easy of attachment.

Still another object of the invention is to provide a button wherein the cover may have a recess centrally thereof, and this recess, in-

stead of being open at the bottom, as in the preferred form, may be imperforate at its bottom, but constructed, nevertheless, so that the plunger may fit within the recess as the button is applied and in the same manner crimp and secure the fastening means with relation to the button head.

As is well known to those skilled in the art, tack buttons are generally applied by the use of a fastening machine, said machine being so arranged that the tacks are fed from one chute, and the button heads from another and the machine so synchronized and timed that the tacks are driven upwardly through the goods into the respective button heads and the point or prong of the tack so deflected that the button head can never thereafter be removed from the cloth or garment, unless, of course, the same is cut off with heavy pliers or tools of a similar nature.

Still another object of the invention is to provide a flexible type button consisting of but the eyelet and the shell which are assembled before the button is attached, and the providing of a cover for the button head into which a plunger may fit to fasten the tacks of the button head.

With these and other objects in view, the invention consists in certain new and novel arrangements and combination of parts as will be hereinafter more fully described and pointed out in the claims.

Referring now to the drawings showing a preferred and modified form of the invention,

Fig. 1 is a top plan view of the button, parts being broken away for the sake of clearness,

Fig. 2 is a vertical section of the button showing a plunger and die in position and deflecting the point of a fastening member during the attaching operation,

Fig. 3 is a similar view after the affixing or attaching operation has taken place,

Fig. 4 is a similar view but showing the button extended, as in possible use, and also showing in dot and dash lines a tilted position thereof,

Fig. 5 is a detail section of assembly of button shell and eyelet,

Fig. 6 is a detail section of the top member or cover before assembly, and

Fig. 7 is a vertical section similar to Fig. 3 of a slightly modified form.

Referring now more particularly to Figs. 1 to 6 inclusive, it will be seen that the button or button head comprises a shell or back 1, which is provided with the hub 2, the outwardly extending portion 3 and the small outer peripheral rim 4.

The bottom of the hub has the restricted 10 circular opening 5 and the slightly upwardly extending rim or wall 6 as may be clearly seen in the several views.

There will also be seen the eyelet 7 which 15 comprises the upwardly extending hollow hub 8 merging with the lower surface of the base 8^a of the eyelet, which base extends upwardly as at 10 forming the peripheral rim and this rim is then turned back on itself to form the outer rim 11.

20 Of course when the parts are assembled, the hub of the eyelet 8 is first placed through the opening 5 in the shell 1, which opening is larger than the external diameter of the hub 8, and the upper edge of the hub 8 is then 25 spun over to form the locking rim 9 as will be readily understood.

With the construction thus far described, it is identical with the companion application, and it will be seen that the head may 30 telescope or move with relation to the eyelet, but cannot become detached as the rim 6 when the button is elongated will contact with and be held against separation by the downwardly extending rim 9 of the hub 8.

35 This allows great flexibility as set out in the companion application and also allows a tilting of the button head so that the same may be easily manipulated by the fingers, and also allows plenty of room for the goods about 40 the button hole or room for the wire loops that may be used over the button head.

45 From this point, however, the button differs from the button shown in the patent to Leonard R. Carley, No. 1,191,944, and from the construction shown in the companion application. In the companion application there is shown an anvil inserted in the button head, but in the present instance, a plunger or die is used in a fastening machine to 50 secure the same results that the little anvil in the companion application performs.

Referring for the moment to Fig. 6, there is shown a small cover 15, provided with a flange 16 which is then placed over the shell 1 and the rim 16 spun inwardly so that the same will tightly lock over the rim 4 of the button back or shell, thus completing the button head.

60 Still referring to Fig. 6 there will be seen centrally of this cover, an opening 17 and the small depending flange 18 forming the walls about the opening. The diameter of the opening is such that a die 19 of a plunger 20 may pass through the opening and crimp 65 the prong 21 of the tack 22. This die 19 may

be recessed as at 23 so that the point of the prong will readily deflect as the tack ascends.

In Fig. 2 I have shown the manner in which the button is to be attached to the cloth 24. The plunger 20 with its die 19 of an attaching machine (not shown) has moved downwardly within the opening 17 of the cover of the button and the cup-shape die is now positioned directly above the hollow hub of the eyelet. The prong 21 of the tack is shown 75 as having just started in its upward movement, it having pierced the goods, passed up within the hub of the eyelet and has engaged the die and the point has started in its deflect- 80 ed path of movement.

In Figs. 3 and 4, the prong is shown as in its final condition, that is crimped and extending partly over the curled rim 9 of the eyelet, thus tightly securing the eyelet to the goods. Of course the eyelet being secured 85 in this manner, the head or shell is free to flex or tilt and also to move vertically with relation to the eyelet, but at the same time cannot become detached therefrom.

90 In the modified form, the construction is identical with the exception of a slight change in the cover plate.

There is the shell 25, eyelet 26, which are held against detachment in the same manner, and there is the cover 27 and the tack 28. 95 This cover, however, has a central pocket or recess 29 and the defining wall 30 which is a little deeper than the wall 18 of the cover 15. Furthermore, the recess, rather than being open at its bottom, has the integral bot- 100 tom 31.

The manner, however, of attaching the button is the same, as the die 19 will pass down within the opening 29 and in the small chamber or recess formed in the cover, and when the button is being attached, the point or prong of its tack 28 when forced upwardly will be deflected and crimped over the upper edge of the hub of the eyelet in exactly the same manner as shown in the preferred 110 form. This small bottom wall 31 will prevent any dirt or foreign matter from getting down into the button and may give a more finished effect than the preferred form, but otherwise there is no distinction between the 115 two.

We have only shown one form of eyelet, as secured to the shell, but any suitable form of eyelet of the same type may be used.

From the foregoing it will be seen that we 120 have produced a button of the flexible type, possessing the advantages of the companion application but being slightly cheaper to manufacture as the necessity of providing the separate anvil for each button is dispensed with.

Many slight changes might be made without in any way departing from the spirit and scope of the invention.

Having thus described our invention, what 130

we claim as new and desire to secure by Letters Patent is:

1. A flexible button comprising an eyelet open at its top, a button head tiltably secured to said eyelet, the head comprising a shell and a cover, said cover provided with a central opening therein, and said opening adapted to receive a die during the attaching operation of the button.
- 10 2. A flexible button comprising an eyelet having an integral hub, a head tiltably and movably secured to the hub of said eyelet the head comprising a shell and cover, said cover provided with an opening therein, the eyelet adapted to permanently receive a fastening member and the opening in said cover adapted to temporarily receive a plunger during the time the fastening member is being forced within the eyelet.
- 20 3. A flexible button comprising an eyelet having an integral hub, a head swivelly and shiftably secured to the hub of said eyelet, the head comprising a shell and a cover, said cover provided with an opening therein and directly over the center of said eyelet, whereby a plunger may be positioned over said eyelet during the attaching operation of the button.
- 30 4. A flexible button comprising an eyelet having a hollow integral hub open at its top, a button head swivelly secured on said hub and also capable of a tilting motion with relation to said eyelet, a cover over said shell and provided with an opening directly over the hub of the eyelet, and said opening adapted to receive a die when the button is being attached to a garment.
- 35 5. A flexible button comprising an eyelet open at its top and a button head, irremov-

ably, shiftably and tiltably secured thereto, the button head comprising a shell having a top cover, and the top cover provided with an opening and a small depending wall around the opening, a tack fastener, and the opening of the cover adapted to receive a 45 plunger during the fastening operation and deflect the point of the tack over the hub of the eyelet to thereby fasten the button to an article.

6. A flexible button comprising an eyelet, 50 said eyelet having a base and an integral upwardly extending hub and the upper end of the hub being outwardly flared, a button head having a hub and having its lower end curled upwardly and adapted to interlock with the 55 curled upper edge of the hub, a cover for said button head and the eyelet adapted to receive a tack member to hold said eyelet and button in position.

7. A flexible button comprising an eyelet, 60 said eyelet having a base and upwardly extending hub and the upper edge of the hub curled outwardly, a button head having a hub, the lower end of which is curled upwardly to interlock with the curled rim when 65 the said button is moved upwardly on the hub of the eyelet, a cover for said button head and said cover provided with a central depressed portion in the cover, said depressed portion adapted to temporarily receive a die 70 and a tack adapted to be deflected when forced into said button head by the said die and thus secure the tack to said eyelet.

In testimony whereof we affix our signatures:

FRANKLIN R. WHITE.
LEONARD R. CARLEY.
